UNITED STATES PATENT OFFICE.

OSCAR W. JOHNSON, OF ROCKFORD, ILLINOIS, ASSIGNOR TO WARD-LOVE PUMP CORPORATION, OF ROCKFORD, ILLINOIS, A CORPORATION OF ILLINOIS.

DEEP-WELL PUMP.

Application filed October 25, 1924. Serial No. 745,739.

This invention relates to the art of devices employed for deep well pumping and has reference more particularly to pumps of the double-stroke type employing two pistons 5 working in opposition to each other.

The primary purpose of my invention is to provide an improved working head for pumps of this type, with a view to obtaining with a simple and compact organization of 10 parts a constant and uniform application of power for pumping and a balanced action in the working head, and a low power consumption and operating and maintenance cost. Another object is to provide a pump 15 head which may be commercially produced at a comparatively low cost and will serve in a practical and efficient manner the purpose intended.

Other objects are to provide an improved 20 arrangement of crank gears, piston rods, and cross-heads, and an improved housing enclosing and supporting said parts and embodying certain structural features desirable in a pump-head as will more fully herein- 25 after appear.

Another purpose is to provide a construction wherein the piston rods and pistons may be quickly and easily removed without dismantling the cross-heads and the operating 30 mechanism thereof.

Another purpose is to provide an improved oiling system for thoroughly lubricating all of the working parts, and an improved means for maintaining a complete 35 separation of the lubricating oil from the water and of the water from the oil.

Other objects and attendant advantages 40 of the invention will be apparent to persons skilled in the art as the same becomes better understood from the following detailed description, taken in connection with the accompanying drawings in which I have illustrated a practical and approved embodiment 45 of the principle of the invention, and where- in—

Fig. 1 is a front elevation of my improved deep well pump with the cylinder broken out and partly in section, and the door of the pump-head housing removed to disclose 50 interior parts;

Fig. 2 is a diagram of the upper and lower

cross-head crank gears and their driving pinion illustrating the balanced action of the piston rods thereon;

Fig. 3 is a detail cross-section through the 55 oil pump, on the line 3—3 of Fig. 1;

Fig. 4 is an enlarged vertical axial section through the working head and its casing; on the line 4—4 of Fig. 1;

Fig. 5 is an elevation of the working head, 60 with the upper cross-head in cross-section and showing the upper and lower cross-heads at their maximum separated position;

Fig. 6 is an enlarged vertical section 65 through the top wall of the housing base above the water discharge chamber, showing the piston rod packing and water drain well therein; on the line 6—6 of Fig. 4;

Fig. 7 is a similar vertical section through 70 the lower cross-head, illustrating the packing for the inner piston rod and water return ducts, etc.;

Fig. 8 is a plane section on the line 8—8 of Fig. 1; and

Fig. 9 is a top plan detail of a divided 75 locking ring for the rod packing in the housing base.

Referring to the drawings, H designates as an entirety an upright rectangular casing or housing for the working head, the same 80 comprising a rear wall 10 (Fig. 4), side walls 11, a detachable top wall 12, a hinged front door 13, and a base 14. The base 14 has a hollow portion shown in Fig. 4 forming a water discharge chamber 15, and on one side of this hollow portion is a separated space shown in Fig. 1 that forms an oil well 16. In the bottom of the water discharge chamber 15 is a port 17 (Fig. 4) that registers with the upper end of a depending cylinder column 18 extending downwardly into the well. As shown, the upper end of the cylinder is threaded into a collar 19 that is attached to the bottom of the housing base 85 by screws 21.

Rigidly mounted in and between the top and bottom members of the housing are a pair of parallel guide rods 22 slidably engaged by upper and lower cross-heads 23 and 24 respectively. As shown in Fig. 5, the upper cross-head 23 is connected by a solid piston rod 25 extending through the 90

lower cross-head and the base of the housing to a lower piston 26 in the column 18; while the lower cross-head 24, as best shown in Fig. 7, is connected to a tubular piston rod 5 27 that extends through the base of the housing and at its lower end is connected to an upper piston 28.

The cross-heads 23 and 24 are slidably mounted on the guide rods 22 and are operated by the following described mechanism which effects simultaneous reciprocations thereof in opposite directions, producing similar simultaneous reciprocations of the pistons 26 and 28. Journalized in and transversely of the opposite side walls 11 of the housing is a power shaft 29 (Figs. 1 and 8), on one overhanging end of which is mounted a drive pulley 31. Fast on the shaft 29 are a pair of spur pinions 32 that mesh with 10 and drive upper and lower pairs of crank gears 33 and 34, respectively. Each of the crank gears 33 has its shaft journaled in a blind bearing 35 formed in a side wall of the housing, and each of the crank gears 34 15 likewise has its shaft mounted in a similar bearing 36 in a side wall. On the inner faces of the gears 33 are wrist pins 37 (Fig. 2) mounted in rollers 38 (Fig. 1) engaged with the opposite grooved sides of the cross-head 23; and the inner faces of the lower crank discs 34 are provided with similar wrist pins 39 mounted in rollers 41 engaged with the opposite grooved sides of the lower cross-head 24. It will be observed by 20 reference to Fig. 2 that the wrist pins 37 and 39 on the upper and lower pairs of crank gears respectively are set 180° apart, so that the cross-heads 23 and 24 always travel simultaneously in opposite directions. 25 This movement balances the thrusts of the load on the housing and bearings of the gears, and insures a steady and uniform reciprocating movement of the pistons in the operation of pumping with no unbalanced 30 strains on the pump-head.

The piston rod 25 of the lower piston 26 is connected to the upper cross-head 23 in the manner clearly shown in Fig. 5. Said cross-head 23 is formed with a central opening of larger diameter than the pistons 26 and 28, in which is fitted a bushing 42 having a flange 42' at its upper end resting on the top of the cross-head, and locked in place by a ring nut 43 on its lower end. The upper end of the rod 25 is threaded, and the same is locked in the bushing 42 by upper and lower nuts 44 and 45 respectively. The lower end of the bushing 42, below the nut 43, is threaded to receive the upper end of a circular apron 46 that forms an oil baffle.

The connection of the upper end of the tubular piston rod 27 to the lower cross-head 24 is clearly shown in Fig. 7. Said cross-head 24 is likewise formed with a central opening of larger diameter than the pistons

26 and 28, in which is fitted a bushing 47 having near its upper end a flange 47' resting on the top of the cross-head and confined at its lower end by a ring nut 48. In the bottom of the bushing 47 is a tapped bore 49 70 into which the upper end of the rod 27 is threaded. On the lower side of the ring nut 48 is a depending flange 51 internally threaded to receive the upper end of another circular apron 52 also constituting an oil 75 baffle.

The rod 25, of course, extends axially through the lower cross-head 24 and its bushing 47. Said bushing is equipped with means to check leakage of oil that may collect on the rod 25 above the lower cross-head down through the latter, and also with means to return any water that may work upwardly through the cross-head, and prevent its mingling with the oil. For the latter purpose, the bushing 47 contains a body of packing 53 surrounding the rod 25 and compressed by a gland 54 which, in turn, is locked in place by an internally threaded cap 55 screwing onto a threaded boss 56 on the upper end of the bushing. The upper end of the bushing 47 is formed with an annular groove 57 in which any water that may pass the packing 53 and cap 55 and flow down over the outer surface of the cap collects, and flows thence downwardly through a duct 58 in the bushing into a similar annular groove 59 in the upper face of a lock nut 61 on the tubular rod 27. Thence the water flows through an oblique duct 62 in said nut onto the outer surface of the tubular rod 27. Any oil collecting on the rod 25 above the lower cross-head is wiped off and prevented from escaping down the rod 25 by an oil wipe 63 mounted in the top of a cap 64 which is screwed onto the upper threaded end of the bushing 47 above the flange 47'. Both the piston rods, of course, pass through the housing base 14, and this latter is provided with means for separately collecting both return water and oil, and for draining off the return water and leading the oil drippings into the oil well 16. The equipment of the base member for these purposes is clearly shown in Fig. 6, wherein it will be seen that the roof portion of the base above the water discharge chamber 15 is formed with a central circular well 65 through the bottom of which is an opening of reduced diameter to receive and fit a sleeve 66 supported in said aperture by a threaded flange 66' on its upper end. Within the sleeve 66 is fitted a bushing 67, the bushing being supported by a radial flange 68 thereon resting on the bottom of a countersink 69 in the upper end of the sleeve, with an interposed annular washer 71. The internal diameter of the sleeve 66 is also greater than the diameter of the pistons 26 and 28, and the bushing 67 is locked in its

seat by a split locking ring 72 that rests on the radial flange 68 of the bushing and is in turn confined by a clamping ring 73 having a depending internally threaded flange 73' screwing onto the upper threaded flange 66' of the sleeve 66. The locking ring 72 as shown in Fig. 9, is formed in symmetrical halves so as to permit the bushing 67 to clear said ring when it is being removed. 5 Within the bushing 67 and surrounding the tubular rod 27 is a body of packing material 74 confined by a gland 75 in turn compressed by a threaded cap 76 screwing onto the threaded upper end of the bushing 67. 10 Fitted down over and around the upper wall portion of the well 65 is the base member 77 of an upstanding oil baffle 78 that also serves to collect and direct into the well 65 water dripping from the lower cross-head. 15 The return water is led to the outside of the housing through a drain pipe 79 (Fig. 4). 20

Describing next the provisions for effecting automatic lubrication of the pump-head mechanism, P designates as an entirety an oil pump in the lower end of the housing H and located in the oil well 16. The pump here shown is of the rotary type, comprising a vertical cylinder 81 (Fig. 3), an eccentric rotor 82 therein, and a piston blade or vane 83, the ends of which sweep past intake and discharge ports 84 and 85 respectively in the cylinder 81. The intake port 84 communicates with a depending intake pipe 86 (Fig. 1) that extends nearly to the bottom of the well 16. The discharge port 85 communicates with a delivery pipe 87 that, as shown in Fig. 1, extends upwardly within the housing and at its upper end enters an oil reservoir or chamber 88 (Figs. 4 and 8) 30 herein shown as formed within a thickened portion of the cover-plate 12 of the housing. The rotor 82 of the pump is driven by a vertical shaft 89 (Fig. 1) having on its upper end a bevel gear 91 meshing with and driven by a bevel gear 92 fast on the drive shaft 29. The pump P maintains the body of oil filling the oil chamber 88 under pressure, and the guide rods, cross-heads, and gears are sprayed with oil from the chamber 88. 40 From the chamber 88 an oil jet is directed against one of the guide rods 22 through a duct 93 (Figs. 4 and 8) and against the other guide rod through a pipe 94. Other pipes 95 and 96 lead from the oil chamber 50 88 to or above the bearings 35 of the upper crank gears 33, whence the oil drips over said gears, the pinions 32 and the lower crank gears 34 and their bearings. Considerable oil collects on the upper surface of the cross-heads 23 and 24, and this oil is passed through oblique ducts 97 and 98 (Fig. 4) to the sleeve bearings of the cross-heads on the rods 22. The baffles 46 and 52 55 guard the piston rods against the splashing of the oil from the cross-head bearings and

also from the oil drip from the cross-heads, and the cylindrical guard or baffle 78 above the water drain well 65 protects the latter from contamination by the oil, so that the descending oil settles on the top of the base 70 14 of the housing around the drain well 65 and flows off one side of the latter into the oil well 16, whence it is returned by the pump to the oil reservoir 88 at the top of the housing for recirculation. Such water, 75 however, as is carried up by the piston rods is caused to flow back, in the manner previously described, along or near the outer surface of the outer piston rod 27, finding its way thence into the drain well 65, whence 80 it is discharged through the drain pipe 79.

In the center of the cover-plate 12 of the housing is a circular opening 99 (Fig. 4) of a diameter slightly larger than the maximum diameter of the cross-head bushings, 85 said opening being closed by a removable lid 101.

From the foregoing it will be apparent that the pistons and their piston rods can be bodily removed from the well tube 18 90 and through the pump-head without disturbing the working positions of the gearing or cross-heads. For such removal of the pistons when required for repairs or renewals, the cover 101 is removed, the ring nut 43 at the bottom of the upper cross-head 23 is backed off, the corresponding ring nut 48 at the bottom of the lower cross-head is backed off, the guard 78 on the base is raised, permitting access to the clamping ring 73 100 for the unscrewing of the latter, the semi-circular sections of the locking ring 72 are then withdrawn, and the pistons, their rods, together with their cross-head bushings and packings may all then be withdrawn lengthwise through the pump head, and when repaired returned in the same manner and the several locking rings 43, 48, 72 and 73 105 replaced. It will thus be apparent that the described structure enables repairs and renewals to the pistons, piston rods, rod packings, etc., to be made without requiring dismantling of the operating mechanism of the head, which represents a great saving of time and expense over pumps of this character heretofore known and used, wherein, when repairs or renewals to the pistons are required, an almost complete dismantling of the operating mechanism of the pump-head 110 must take place. 115

From the foregoing it will be seen that my present invention provides a deep well double-stroke pump characterized by a balanced action of the driving means, a low motor load, simple, compact and rigid construction, low cost of production, the complete incasing of the working parts of the head protecting the latter from dust, a positive feed of oil from an overhead feed or chamber, which eliminates grease cups, 120 125 130

sight feed oilers, etc., automatic circulation of the lubricating oil, requiring replenishment of the oil only at long intervals, and the provision for removing the pump pistons or plungers through the cross-heads without removing the main housing from its base or disturbing the cross-heads or their operating gears and, finally, provisions for keeping the lubricating oil and the water pumped entirely separated.

While I have herein shown and described a practical and useful embodiment of the principle of my invention it is manifest that the specific structural details are capable of wide variation and modification within the principle of the invention and without sacrificing any of the benefits and advantages secured thereby. Hence, I do not limit the invention to the particular structure and organization shown and described for purposes of illustration, but reserve all such variations and modifications as fall within the spirit and purview of the appended claims.

25 I claim—

1. In a deep well pump of the type described, the combination of a pump-head frame, upper and lower crank-gears journaled in said frame, a driving pinion meshing with both said crank-gears, and telescoping piston-rods operatively connected to said crank-gears for simultaneous reciprocation in opposite directions.

2. In a deep well pump of the type described, the combination of a pump-head frame, upper and lower pairs of crank-gears journaled in said frame, a drive shaft journaled in and transversely of said frame, pinions on said shaft meshing with upper and lower gears respectively of said pairs for driving each pair together, and a pair of piston-rods operatively connected at opposite sides thereof to said upper and lower pairs of crank-gears respectively for simultaneous reciprocation in opposite directions.

3. In a deep well pump of the type described, the combination of a pump-head frame, upper and lower pairs of opposed crank-gears journaled in said frame, a drive shaft journaled in and transversely of said frame, pinions on said drive shaft meshing with upper and lower gears respectively of said opposed pairs, vertical guides in said frame, upper and lower cross-heads slidably mounted on said guides, wrist pins one hundred and eighty degrees apart on said pairs of crank-gears respectively engaged with said cross-heads, and piston-rods respectively connected to said cross-heads.

4. In a deep well pump of the type described, the combination of a pump-head frame, upper and lower pairs of crank-gears journaled in said frame, a drive shaft journaled in and transversely of said frame, pinions on said drive shaft meshing with upper

and lower gears respectively of said pairs, vertical guides in said frame, upper and lower cross-heads slidably mounted on said guides, wrist pins one hundred and eighty degrees apart on said crank-gears respectively engaged with said cross-heads, a piston-rod connected to said upper cross-head, and extending through said lower cross-head, and a tubular piston-rod connected to said lower cross-head and surrounding said first-named piston-rod.

5. In a deep well pump, the combination of a head frame, cross-head guides therein, a cross-head mounted on said guides, a bushing removably mounted in said cross-head, a piston rod connected to said bushing, and a piston on said rod; said bushing being of greater diameter than said piston whereby said bushing, rod and piston may be bodily passed through said cross-head.

6. In a deep well pump, the combination of a head frame, cross-head guides therein, upper and lower cross-heads mounted on said guides, bushings removably mounted in said cross-heads, a piston rod connected to said upper bushing and extending through the lower bushing, a tubular piston rod connected to said lower bushing and encircling said first-named piston rod, and pistons on said rods; both of said bushings being of greater diameter than said pistons whereby said bushings, rods and pistons may be bodily passed through both of said cross-heads.

7. In a deep well pump, the combination of a head frame including a base, cross-head guides in said frame, upper and lower cross-heads mounted on said guides, bushings removably mounted in said cross-heads and base, a piston rod connected to said upper bushing and extending through the lower cross-head and base bushings, a tubular piston rod connected to said lower cross-head bushing and passing through said base bushing and encircling said first-named rod, and pistons on said rods; all of said bushings being of greater diameter than said pistons whereby said bushings, rods and pistons may be bodily passed through said base and cross-heads.

8. In a deep well pump, the combination of a head frame, cross-head guides therein, a centrally apertured cross-head mounted on said guide, a bushing fitted to said aperture and formed with an upper radial flange overlying the upper side of said cross-head and a threaded lower end extending below said cross-head, a ring nut on said threaded lower end locking said bushing in said cross-head, a piston rod connected to said bushing, and a piston on said rod; said bushing being of greater diameter than said piston whereby, on the removal of said locking ring, said bushing, rod and piston may be bodily removed endwise through said cross-head.

9. In a deep well pump, the combination

- of a pump-head housing, pump gearing, including a pair of guides and a cross-head slidably engaged with said guides, in said housing, said cross-head formed with oil ducts between the top and the guide bearings thereof, an oil chamber at the top of said housing, and means for distributing oil from said chamber over said pump gearing.
10. In a deep well pump, the combination of a pump-head housing having a water discharge chamber in the base thereof, pump gearing in said housing including a cross-head and a piston rod extending therefrom through said water discharge chamber, means in said housing for circulating lubricating oil over said pump gearing, and means for preventing admixture of said lubricating oil with water adhering to said piston rod.
15. In a deep well pump, the combination of a pump-head housing having a water discharge chamber, an oil well, and a water drip collecting well in the base thereof, pump gearing in said housing including a cross-head, and a piston rod extending therefrom through said drip well and said water discharge chamber, means in said housing for circulating lubricating oil over said pump gearing, means for directing oil drip from said gearing into said oil well, means for directing water drip from said piston rod and cross-head into said drip well, and a water drain from said last-named well to the exterior of said housing.
20. 11. In a deep well pump, the combination of a pump-head housing having a water discharge chamber, an oil well, and a water drip collecting well in the base thereof, pump gearing in said housing including a cross-head, and a piston rod extending therefrom through said drip well and said water discharge chamber, means in said housing for circulating lubricating oil over said pump gearing, means for directing oil drip from said gearing into said oil well, means for directing water drip from said piston rod and cross-head into said drip well, and a water drain from said last-named well to the exterior of said housing.
25. 12. In a deep well pump, the combination of a pump-head housing having a water discharge chamber, an oil well, and a water drip collecting well in the base thereof, pump gearing in said housing including upper and lower cross-heads, and piston rods extending therefrom through said drip well and said water discharge chamber, an oil chamber at the top of said housing, means for distributing oil from said chamber over said pump gearing, means for directing oil drip from said gearing into said oil well, an oil pump for forcing oil from said oil well to said oil chamber, means for directing water drip from said piston rods and lower cross-head into said drip well, and a water drain from said last-named well to the exterior of said housing.
30. 13. In a deep well pump, the combination of a pump-head housing, pump gearing, including cross-head guides and a cross-head slidably mounted on said guides, in said housing, a piston rod connected to and depending from said cross-head, means for supplying lubricating oil to said pump gearing, and an oil baffle encircling said piston rod below said cross-head.
35. 14. In a deep well pump, the combination of a pump-head housing, pump gearing, including cross-head guides and a cross-head slidably mounted on said guides, in said
- housing, a piston rod connected to and depending from said cross-head, means for supplying lubricating oil to said pump gearing, and an annular apron constituting an oil baffle attached to the lower side of said cross-head and surrounding said piston rod.
40. 15. In a deep well pump, the combination of a pump-head housing, pump gearing, including cross-head guides and upper and lower cross-heads slidably mounted on said guides, in said housing, coaxially disposed solid and tubular piston rods connected to and depending from said upper and lower cross-heads, respectively, means for supplying lubricating oil to said pump gearing, and annular aprons constituting oil baffles attached to the lower sides of said cross-heads respectively around said piston rods.
45. 16. In a deep well pump, the combination of a pump-head housing including a hollow base formed with a water discharge chamber, pump gearing, including cross-head guides and upper and lower cross-heads slidably mounted on said guides, in said housing, coaxially disposed solid and tubular piston rods connected to and depending from said upper and lower cross-heads, respectively, means for distributing lubricating oil from the top of said housing over said gearing, annular aprons constituting oil baffles attached to the lower sides of said cross-heads respectively around said piston rods, and an upstanding annular oil baffle on said housing base encircling said piston rods and adapted for telescopic engagement with the oil baffle on said lower cross-head on the descending travel of the latter.
50. 17. In a deep well pump, the combination of a pump-head housing including a hollow base formed with a water discharge chamber, pump gearing in said housing, a piston rod extending from said pump gearing through said water discharge chamber, a cylindrical discharge column connected at its upper end to the base of said housing and communicating through a port in the latter with said water discharge chamber, and a piston on the lower end of said piston rod in said discharge column.
55. 18. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, and means for conducting seepage of water from said chamber to the lower side of said cross-head.

19. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, means for conducting seepage of water from said chamber to the lower side of said cross-head, a drip well below said lower cross-head in said housing for collecting drippings from the cross-head, and means for conducting the water collecting in said well to the exterior of said housing.
20. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, means for conducting seepage of water from said chamber to the lower side of said cross-head, a drip well below said lower cross-head in said housing for collecting drippings from the cross-head, means for conducting the water collecting in said well to the exterior of said housing.
21. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, means for conducting seepage of water from said chamber to the lower side of said cross-head, a drip well in the upper wall of said discharge chamber for collecting drippings from the under side of said lower cross-head, and means for conducting the water collecting in said well to the exterior of said housing.
22. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, means for conducting seepage of water from said chamber to the lower side of said cross-head, a drip well below said lower cross-head in said housing for collecting drippings from the cross-head, means for conducting the water collecting in said well to the exterior of said housing, an annular baffle wall rising from said well about said rods and in spaced relation thereto.
23. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a stuffing box in the lower cross-head through which the inner rod operates, an auxiliary stuffing box on said lower cross-head having said inner rod operating therethrough, said stuffing boxes having a closed chamber therebetween, means for conducting seepage of water from said chamber to the lower side of said cross-head, and a depending baffle wall on said cross-head extending about said rods in spaced relation thereto whereby the drainage of seepage of water occurs within the enclosure formed thereby.
24. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a water sealing packing in said lower cross-head through which said inner rod is arranged to reciprocate, an oil sealing packing above said last mentioned packing about said rod and in spaced relation to the first packing to afford

- a closed chamber therebetween, a depending baffle wall on said upper cross-head extending about said inner rod to prevent the splashing of oil onto said rod, means communicating with said chamber for draining water seepage therefrom to the under side of said lower cross-head, and means for directing the water dripping from the lower side of said cross-head to the exterior of said housing. 25
25. In a deep well pump, the combination of a pump head housing, pump gearing in said housing including cross-head guides and upper and lower cross-heads slidably mounted on said guides, a pair of telescoping piston rods connected to said cross-heads, the outer piston rod being connected with the lower cross-head and the inner one with the upper cross-head, a water sealing packing in said lower cross-head through which said inner rod is arranged to reciprocate, an oil sealing packing above said last mentioned packing about said rod and in spaced relation to the first packing to afford a closed 20 chamber therebetween, a depending baffle wall on said upper cross-head extending about said inner rod to prevent the splashing of oil onto said rod, means communicating with said chamber for draining water seepage therefrom to the under side of said lower cross-head, means for directing the water dripping from the lower side of said cross-head to the exterior of said housing, and baffle means beneath said lower cross-head for preventing the splashing of oil onto said outer rod and forming an enclosure for the water dripping from said lower cross-head. 30
26. In a deep well pump, the combination of a pump head housing, pump gearing in said housing including a pair of guides and upper and lower cross-heads slidably mounted on said guides, a bushing removably mounted in each of said guides, a pair of telescoping piston rods connected to the bushings in said cross-heads and bearing pistons at their lower ends, said bushings being of greater diameter than said pistons whereby said bushings, rods, and pistons may be bodily passed through both of said cross-heads, a water sealing packing in the bushing of said lower cross-head about the inner piston rod, an oil sealing packing supported on said bushing above the first packing in spaced relation thereto whereby to afford a closed chamber between said packings, a passage provided through said bushing communicating with said chamber to drain any seepage of water therefrom to the under side of said cross-head, and means for conducting the drippings from the under side of said cross-head to the exterior of said housing. 35
27. In a deep well pump, the combination of a base, a head frame thereon, cross-head guides therein, a cross-head mounted on said guides, a bushing removably mounted in said cross-head, a piston rod connected to said bushing, a piston on said rod, and a second bushing removably mounted in said base having said rod operating therethrough, both of said bushings being of greater diameter than said piston whereby the latter may be passed bodily through the base and the cross-head, and the second named bushing being of a size to pass through the opening for said first named bushing in said cross-head. 40
28. In a deep well pump, the combination of a head frame, cross-head guides therein, upper and lower cross-heads mounted on said guides, bushings removably mounted in said cross-heads, a piston rod connected to said upper bushing and extending through the lower bushing, a tubular piston rod connected to the lower bushing and telescoping with the first rod, and pistons on each of said rods, both of said bushings being of greater diameter than said pistons so that the latter may be passed bodily through the bushing openings in said cross-heads and the lower bushing being of a size to pass through the opening for the upper bushing in the upper cross-head. 45
29. In a deep well pump, the combination of a base, a head frame thereon, cross-head guides in said frame, upper and lower cross-heads mounted on said guides, bushings removably mounted in said cross-heads and base, a piston rod connected to said upper bushing and extending through said lower cross-head and base bushings, a tubular piston rod connected to the lower cross-head bushing and telescoping with said first named rod and passing through said base bushing, and pistons on each of said rods, all of said bushings being of greater diameter than said pistons whereby the latter may be passed bodily through the bushing openings in the base and cross-heads, and said bushing in the lower cross-head being of a size to pass through the bushing openings in the upper cross-head while the bushing in said base is of a size to pass through the bushing openings in both of said cross-heads. 50

OSCAR W. JOHNSON.
